LLP(57) **CLAIM**

We claim the ornamental design for an optical lens, as shown and described.

DESCRIPTION

FIG. 1 is perspective view of an optical lens showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a sectional view taken along the line A-A' of FIG. 8; and,

FIG. 10 is a sectional view taken along the line B-B' of FIG. 8.
